UNITED STATES PATENT OFFICE.

HERMAN PICHEL, OF NEW YORK, N. Y., ASSIGNOR TO SAMSTAG & HILDER BROS., OF NEW YORK, N. Y., A CORPORATION OF NEW YORK.

DESIGN FOR A HAIR ORNAMENT.

49,397.

Specification for Design.

Patented July 18, 1916.

Application filed May 16, 1916. Serial No. 97,949. Term of patent 3½ years.

To all whom it may concern:

Be it known that I, HERMAN PICHEL, a citizen of the United States, residing in the borough of Manhattan, city of New York, in the county of New York and State of New York, have invented a new, original, and ornamental Design for a Hair Ornament, of which the following is a specification, reference being had to the accompanying drawing, forming part thereof.

In the drawing: Figure 1 is an elevation of a hair ornament showing my new design. Fig. 2 is a sectional view on line 2—2 of Fig. 1.

I claim:

The ornamental design for a hair ornament as shown.

HERMAN PICHEL.
